UNITED STATES PATENT OFFICE.

GEORGE H. MILLER, OF BROOKLYN, NEW YORK.

PRINTING-PRESS.

1,105,816.

Specification of Letters Patent. Patented Aug. 4, 1914

Application filed July 11, 1913. Serial No. 778,500.

To all whom it may concern:

Be it known that I, GEORGE H. MILLER, a citizen of the United States, and resident of Brooklyn, in the county of Kings and State of New York, have invented certain new and useful Improvements in Printing-Presses, of which the following is a specification.

This invention relates to printing presses and more especially to presses adapted to print two or more colors, and consists of simple means capable of being attached to the ordinary printing press at a very moderate cost, which with the proper arrangements of the forms, will reduce the press-work to one-half the impressions usually required, as will be more fully described in the following specification, set forth in the claim and illustrated in the accompanying drawings, wherein:

Figure 1 is a plan view of the bed and ink plate of a cylinder press. Fig. 2 is a side view of the same. Fig. 3 is an enlarged plan view of the ink plate. Fig. 4 is a longitudinal sectional view of the same. Fig. 5 is a front end view of the plate. Fig. 6 is a perspective view of the filling strip.

The two-color printing press now commonly used requires nearly double the amount of mechanism required for a single color press and the impressions are made at different times. Nevertheless two impressions are necessary, one for each color at different times as the paper passes through the press.

The present invention provides for a simple adaptation of the one color press so that it can be used for two colors and at the same time but half the usual number of impressions are necessary. In order to accomplish this end the forms for the two colors are operated side by side instead of following each other, and the fountain is divided by a partition so as to contain two different inks and the ink plate is also divided to separate these inks.

The drawings show the end portion of a cylinder printing press with the ordinary reciprocating bed 10 carrying the chase 11 with its form, and extending beyond the bed is the ink plate 12 which may be secured to the longitudinally moving rails 13 by screws for removal if desired. The ink plate is provided at about a central point with a longitudinal groove 14 and into same is fitted a strip 15 flush with the surface of

the plate and having on its lower side studs 16 to fit into perforations in the groove and prevent the longitudinal movement of the plate. The studs 16 are inclined and the front end of the plate carries a gravity latch 17 to hold the strip against movement in that direction.

The ink fountain 18 may be of the usual type and provided with one or more blocks 19 to completely fit between the walls of the fountain so that different colored inks may be contained in the compartments formed by the block. The usual distributing rollers 20 are employed but the composition is cut away midway of their length or at a point corresponding with the block 18. This removed part of the rollers also corresponds with the groove 14 of the ink plate so that when two colors of ink are used, they are effectually separated on the plate and are thoroughly intact. The ink being taken up by rollers 21 they are also practically divided and other rollers may be used and set slightly at an angle to more thoroughly distribute the ink which is to be applied to the forms in the chase 11.

In adapting this device for printing in two colors the two forms 22 and 23 are placed side by side but their tops are reversed. Different colored inks are placed in the compartments of the fountain 17 and distributed on the two sides of the ink plate and finally to the two forms. In case red ink is used on the form 22 and black on form 23 they are prevented from mixing and blending by the groove 14 and half of the desired number of sheets are printed at the same time from the two forms. If a job of a thousand sheets is desired, five hundred impressions are made with one end of the sheet from the red form and the other end from the black form. The five hundred sheets are again run through the press after being turned so that the black impressions will receive the imprint of the red side and vice versa, the two colors being interlined or mingled as desired but one thousand two-color sheets are thus obtained with but one thousand impressions where two thousand impressions have heretofore been required.

The mechanism as above described may be used for printing small forms in one color or it may be used for several small forms at one time in a single color as for two colors, but when it becomes necessary to use

a large form the block 19 is removed and whole and entire inking rollers are substituted.

The ink plate 12 is adapted for use for a single color by simply filling the groove 14 with the strip 15 and locking the same therein by means of the latch 17. The strip being flush with the balance of the plate the latter becomes to all intent and purpose a single ink plate of large surface.

It is obvious that the device may be so modified as to apply it to presses where more forms than two are used, or the details may be altered or changed without departing from the essential features above described or the scope of the appended claim.

In actual use it may not be found necessary to cut away the composition rollers 20 and 21 but the grooved vibrating rollers 20' and 21' in connection with the block 19 and

groove 14, may be sufficient to separate the inks without mutilating the regular inking and distributing rollers.

What I claim as new and desire to secure by Letters Patent is:

In a printing press, the combination with a fountain for inks, of a block to loosely fit within same and divide the inks, rollers with grooves to correspond with the location of the block, an ink plate with a groove 30 and inclined perforations, a strip with studs for the perforations and a gravity latch to hold the strip in the groove.

Signed at New York in the county of New York and State of New York this 30th day of June A. D. 1913.

GEORGE H. MILLER.
